UNITED STATES PATENT OFFICE.

PHILIP S. REID, OF READING, PENNSYLVANIA, ASSIGNOR TO THE READING STANDARD MANUFACTURING COMPANY, OF PENNSYLVANIA.

DESIGN FOR A FORK-CROWN.

SPECIFICATION forming part of Design No. 29,874, dated December 27, 1898.

Application filed November 25, 1898. Serial No. 897,459. Term of patent 7 years.

To all whom it may concern:

Be it known that I, PHILIP S. REID, a citizen of the United States of America, and a resident of Reading, county of Berks, State of Pennsylvania, have invented and produced a new and original Design for a Fork-Crown for Bicycles, of which the following is a specification, reference being had to the accompanying drawings, forming part thereof

- o Figure 1 is a longitudinal elevation of a fork-crown of my new design. Fig. 2 is a plan view of the same. Fig. 3 is an end elevation.

The essential features of my new design consist in the general shape and conformation of the unitary fork-crown, as illustrated in the drawings, and comprise the hollow cylindrical body *a*, having fork-arm projections *f* depending from a flat base *e*, which forms a triangu-

lar junction with the curved surface of the cylindrical body, and a fork-tube connection *b*, forming a low cylindrical pillar rising from a rectangular saddle-block *c*, the flat vertical faces *d* of which, extending to the horizontal axial plane of the cylindrical body *a*, form suitable surfaces for inscriptions or ornamentation.

What I claim is—

The design for a fork-crown substantially as shown and described.

Signed by me, at Reading, Pennsylvania, this 17th day of November, A. D. 1898.

PHILIP S. REID.

Witnesses:

HARRY H. BOYER,
ADAM L. OTTERBEIN.
